UNITED STATES PATENT OFFICE.

ERNST BEHR, OF SARATOGA SPRINGS, NEW YORK.

LEAF-TURNING DEVICE.

1,353,015.

Specification of Letters Patent. Patented Sept. 14, 1920.

Application filed August 6, 1919. Serial No. 315,706.

To all whom it may concern:

Be it known that I, ERNST BEHR, a citizen of the United States, residing at Saratoga Springs, in the county of Saratoga and State of New York, have invented certain new and useful Improvements in Leaf-Turning Devices; and I do hereby declare the following to be a full, clear, and exact description of the invention, such as will enable others skilled in the art to which it appertains to make and use the same.

This invention relates to improvements in what are generally termed leaf turners, more especially for sheet music for pianos or stands.

It has for its object to provide for the ready turning of the sheets of music without the direct interposition of the hand or its contact with the sheets.

A further object is to carry out these ends with facility and expedition and to provide an inexpensive and simple device for its intended purpose.

The invention consists of certain instrumentalities and features of construction substantially as hereinafter more fully disclosed and particularly defined by the appended claims.

In the accompanying drawings is illustrated the preferred embodiment of my invention wherein it will be understood that various changes and modifications as relate to the detailed construction and arrangement of parts may be made without departing from the spirit or scope of the invention as embraced in the claims.

In the drawings:

Figure 1 is a front elevation of my invention, partly in section.

Fig. 2 is an end elevation thereof.

Fig. 3 is a detailed end view thereof, showing more particularly the means providing for the release of the spring-containing casings in allowing of the shifting of the leaf turner.

Fig. 4 is a plan view of my invention.

Fig. 5 is a horizontal section thereof, taken just above the lower spring containing casing.

Fig. 6 is a fragmental perspective view on a somewhat enlarged scale showing more fully certain parts of Fig. 3.

Figs. 7, 8, 9, 10, 11 and 12 are further detail views, in plan and section further disclosing the elements of Fig. 3 more particu-

larly as to the different positions assumed thereby during the operation of the machine.

Figs. 13, 14 and 15 represent a side elevation, a front elevation and a plan view of my invention as applied for use with respect to a stand.

In carrying out my invention, I employ or provide what may be termed a bracket or carrier 1, preferably consisting of a transverse member and opposite end members at right-angles to the latter, preferably in a single structure. The transverse member has inserted centrally therethrough the nut-equipped end of a preferably bolt-like or pin member 2, this being rigidly secured thereto, and upon the latter member is sleeved a bushing 3, one end of the pin or bolt-member being preferably flanged or enlarged, the resultant enlargement being angular and let into a corresponding recess or socket in one end of said bushing for the retention of said pin 2. The opposite end of said bushing is laterally extended, the resultant extension being cogged or toothed, thus forming a gear or pinion 3^a which is intermeshed with a small gear or pinion 4 for winding or putting under tension a spring 5, suitably connected to the bushing 3 and to a casing 6 carried upon a shoulder of the bushing, as required in moving or turning the leaf-turner with the desired music sheet or sheets, in one direction as presently more clearly seen.

Similarly a second spring 7 is housed in a second casing 8 carried upon a shoulder of a bushing 9 having a cogged or toothed extension forming a gear or pinion 10 which intermeshes with a pinion or gear 11 for winding or putting under tension the second spring 7, as required in moving the leaf-turner, with the desired music-sheet or sheets, oppositely to the direction in which the aforesaid leaf-turner is turned or moved, as may become necessary. The gearings 4 and 11 have their shafts 4^a and 11^a, respectively, suitably journaled in the carrier 1 and arranged to be readily actuated by hand; also said gearings are held against reverse movement by means of pawls or detents 4^b, 4^c pivoted upon the carrier 1 and engaging said gearing, respectively. A spacing tubular member 4^d sleeved upon the bushing 3 is interposed between, and retains the casings 6 and 8 in position with re-

105

110

spect to the other parts of the device. Suitable rotary bearing members or balls 8^a, are interposed between the spring-containing casings and the general inclosing therefor in order to reduce friction and for the smooth movement of said casings.

The leaf or music-sheet turner 12, only one being shown, it being understood that any number may be used, includes principally a preferably L-shaped member 12^a and a hand actuated member 12^b, said members 12^a, 12^b being adapted to be applied so as to be moved horizontally in an arcuate plane to the pin or bolt-like member 2, and to a preferably laterally extended headed screw 13 threaded into the lower end of said pin, the screw 13 serving to hold the sheet or leaf-turner centrally its pivoted point or axis of rotation upon the pin. The member 12^a of the leaf-turner is also adapted, being apertured, to receive the bushing 9 carrying the gearing 10 for actuating the spring 7. The hand-actuated member 12^b is also provided with preferably key-hole like slots 14, the purpose of which will be seen hereinafter.

A frame 15, resting at its lower end upon the present music sheet rest of pianos and carrying an adjusting rack 16 adapted to conveniently provide for the accommodation of the device for playing from a book instead of from sheet-music, is suitably fixed to the carrier 1, the adjustment between the frame and rack being effected preferably by means of keeper or loop terminals 15^a on said rack, receiving the side members of said frame, and set screws 16^a working in said loop-terminals and engaging the frame side members, as clearly shown in Fig. 1. 40 Suitable stopping slides or members 17, 17^a are provided, two upon each spring-containing casing 6 and 8, so arranged that by their coöperation with other parts or instrumentalities presently referred to, they 45 will restrict the movement of each casing to a predetermined arc in effecting the actuation of the leaf or sheet turner as more fully disclosed hereinafter.

Levers 18, 18^x are oppositely fulcrumed, 50 with respect to the carrier 1 and the spring-containing casings 6, 8, upon a rod or shaft 18^a supported in the carrier, and arranged for coöperation with the stopping slides or members 17, as presently seen and for reverse actuation, as also presently seen. The levers 18, 18^x are connected preferably by wires 18^b, say three-sixteenths of an inch gage, to opposite levers 19 suitably fulcrumed just above the present music sheet 55 rest of pianos, said levers 19 being provided each with what may be termed as a hanger 20, having a button-hole like terminal 21 to provide for indicating which leaf to turn.

The spring casings are provided with pins 60 or plungers 22^a, 22^x adapted to be engaged

respectively by the levers 18, 18^x at one end of each, as will be apparent from Figs. 3, 4 and 5^a. The pins or plungers are preferably reduced at reversed opposite ends for actuation by the levers 18, 18^x. The reduced 70 ends of said pins are passed through apertures in the bottoms of the spring-containing casings to extend therebelow for engagement with the leaf or sheet turner to cause the latter to travel a predetermined distance, or one half way around. Springs 23, 23^a are applied to the pins or plungers for automatic retention in initial position and automatic relaxation, or disengaging movement, when pressure is removed therefrom. 75 When the pins or plungers 22^a, 22^x are depressed or acted upon by the levers 18, 18^x, which, as before stated, allow of the required movement of the leaf or sheet turner, spring-pressed levers 24, 24^a suitably pivoted upon the spring-containing casings, immediately come into action behind, and hold said pins or plungers in such depressed position until the pins or plungers are released from said levers. Simultaneously with the 80 engagement of the levers 18, 18^x, with the pins or plungers 22^a, 22^x, said pins or plungers act upon the stopping slides or members 17, 17^a, which allow the turning of the spring-containing casings; concurrently 85 therewith, however, said pins or plungers, which are rearward of the leaf-turner, force the leaf-turner out of engagement with the levers 24, the parts thus resuming their initial position for a subsequent like operation 90 when the leaf or sheet turner is to be again brought into action.

In Figs. 13, 14, and 15, is shown the application of my leaf or sheet turner to a music sheet stand 25, 25^a designating the support 105 or upright thereof, the stability of which in upright position depending upon the tripod or feet 26. Flexible connections or members 27 are provided between pedal-equipped levers 27^x, pivoted upon said feet 110 or tripod, and levers 18^{xx} corresponding to the levers 18, 18^x above referred to, said elements having associated therewith, as suggested by the foregoing primary embodiment of the invention, a carrier or bracket 115 28^a, and in practice coöoperating parts as also set forth therein, and a rod 18^{cc} corresponding to the rod 18^a and supported by the carrier 28^c, said rod 18^{cc} forming the pivot for the lever 18^{xx}. The flexible connections 27 120 and the stand support 25 have adjustably applied thereto, as at 29, means similar to 15^a, 16, 16^a of the primary disclosure and for the application of a frame and rack thereto.

From the foregoing description and illustration as exemplified by the accompanying drawings, it is believed that the advantages and facilities of my invention have been fully disclosed and made readily appreciable.

Having described my invention, what I claim and desire to secure by Letters Patent is:

1. The combination in a leaf-turner, of a
5 spring-actuated member, means for containing
said spring-actuated member, means pro-
vided for effecting the movement of said
spring-actuated member, including a stop-
ping slide on said spring-containing means,
10 adapted to temporarily retain the latter
against movement, a plunger which serves to
actuate the latch, a lever adapted to depress
said plunger, an additional spring-pressed
lever adapted to hold the plunger depressed
15 until released from its depressing lever, said
plunger, simultaneously with the engage-
ment therewith of said depressing lever, act-
ing upon said sliding stop to allow the turn-
ing of said spring-containing means and to
20 force the leaf-turner out of engagement with
said additional lever.

2. The combination in leaf-turner, of
spring actuated members, means for carrying
said spring actuated members, and means
25 including manually actuated members, stop-
ping slides and spring-pressed pins arranged
upon said spring-actuated members and
adapted to engage said spring-actuated mem-
bers, levers carried by said spring-actuated
30 members for temporary engagement with
said pins, said levers being adapted to re-
lease said pins, said pins being adapted to
act upon said stopping slides to allow the
turning of said spring-actuated members,
35 said pins being adapted to force said spring-
actuated members out of engagement with
said levers.

3. The combination in a leaf-turner, of
a stand, spring-actuated means, means for
40 containing said spring-actuated means, ap-
plied to said stand and means for manually

actuating said spring-actuated means from
said stand, means for effecting the movement
of said spring-actuated means, including a
stopping slide on said spring-containing 45
means, adapted to temporarily retain said
spring-containing means against movement;
a plunger which serves to actuate the latch,
a lever adapted to depress said plunger, an
additional lever adapted to hold said plunger 50
depressed until released from its depressing
lever, said plunger, simultaneously with the
engagement therewith of said depressing
lever, acting upon said sliding stop to allow
the turning of said spring-containing means 55
and to force the leaf-turner out of engage-
ment with said additional lever.

4. The combination in a leaf-turner, of a
spring-actuated member, means for carrying
said spring-actuated member, and means en- 60
gageable with said spring actuated member
for automatically controlling the movement
of said spring-actuated member, including a
manually actuated member, a stopping slide
and a spring-pressed pin arranged upon said 65
spring-actuated member, said pin being
adapted to extend through said spring-actu-
ated member for engagement with the leaf-
turner, and a pivoted member carried by said
spring-actuated member for the temporary 70
retention of said pin against movement, said
pivoted member subsequently releasing said
pin, said pin being adapted, simultaneously
with the engagement of said pivoted member
therewith, to act upon said stopping slide to 75
allow the turning of said spring-actuated
member, concurrently with which said pin
forces said leaf-turner out of engagement
with said pivoted member.

In testimony whereof, I affix my signature. 80

ERNST BEHR.
